UNITED STATES PATENT OFFICE

AXEL MORCK, OF BROOKLYN, NEW YORK.

HORSESHOE.

1,250,485.

Specification of Letters Patent. Patented Dec. 18, 1917.

Original application filed February 4, 1915, Serial No. 6,091. Divided and this application filed January 31, 1916. Serial No. 75,377.

To all whom it may concern:

Be it known that I, AXEL MORCK, a citizen of Sweden, and resident of the borough of Brooklyn, in the county of Kings and 5 State of New York, have invented certain new and useful Improvements in Horseshoes, of which the following is a specification.

The present invention has already been 10 disclosed by me in a co-pending application for patent, filed on the 4th day of February, 1915, Serial No. 6,091, of which this is a division.

As previously divulged in the patent application aforesaid, the subject matter hereof consists of an improved horseshoe, provided with separable calks, which in the present case are claimed only so far as they relate to the posterior portion of the application. The calk pertaining to the anterior member is covered by claims allowed in Serial No. 6,091, above noted.

To obviate unnecessary repetition and consequent superfluity of statement herein, 25 the object of the invention may be briefly said to provide a heel calk which is readily detachable either for sharpening or for replacement; can be applied or removed easily by any horseman or teamster of ordinary 30 intellect with the aid of common tools, and admits of being drop-forged, from light steel, at a low rate of expense comparing favorably with that involved in the production of the usual horseshoes.

The novel features of the invention reside 35 in the peculiar construction, arrangement, and combinations of parts hereinafter described in their preferred forms, particularized in the appended claims, and exemplified in the drawing hereto annexed, in which:

Figure 1 is a bottom plan view illustrating one embodiment of the invention; parts thereof being in section;

Fig. 2 is a fragmentary side elevation, partly sectioned, showing the same species of heel calk represented in connection with the preceding view;

Fig. 3 is a cross section on the line 3—3, 50 Fig. 2 of a quarter of the horseshoe provided with a calk of the said species;

Fig. 4 is an end view of the said heel calk, as it appears previously to being imparted the shape represented in Fig. 3;

Fig. 5 is a bottom plan of the rear portion of the said quarter, embodying a modification of the invention; and

Fig. 6 is a transverse section on the line 6—6 of Fig. 5, looking in the direction pointed out by the arrows in the latter-named figure.

As in the prior case aforementioned, the numeral 11 herein designates the bottom or under face of the quarters or lateral portions of a horseshoe, the same being formed 65 with the usual creases or fullering 12, having dual series of nail-holes as 13.

Forwardly, the shoe is furnished with a toe calk, the construction of which has been shown in detail and minutely described in 70 the said patent application, Serial No. 6,091, covering the same. Suffice it to say, for the purposes of this specification, that the said toe calk is held to the front part of the horseshoe by a pair of jaws and a wedge 75 key respectively designated herein by the reference numerals 28, 29 and 31, as formerly.

Referring to the rear end of the shoe, and looking particularly at Figs. 1 and 3 of the annexed drawing, it will be seen that the 80 uncovered or sectioned quarter therein represented is dovetailed in two directions, namely, lengthwise with a rearwardly-increasing taper 37, and crosswise with sides 38, 39 beveled upward and inward. The 85 outer side 38, Fig. 3, has a straight portion or marginal offset 40, the specific purpose whereof will be explained hereinafter.

To the tapering end 37 of the said quarter of the horseshoe is attached a removable 90 heel calk 41, depending from a plate or backing 42. The latter is provided with a pair of jaws 43, 44, one of which, preferably that located on the outside of the shoe, will stand away from a lateral bevel thereof, 95 as 38, in a manner to permit insertion of an intervening wedge key 45. By forcibly driving in this key, the upper surface of the said plate or backing together with the jaw 43 thereon, will be drawn tight against the bottom face 11 of the shoe, and the lateral bevel 39 aforesaid, respectively. As indicated in Fig. 1, the forward extremity 48 of the wedge 45 may be bent over the adjacent edge of the jaw 44, so as to prevent the parts 100 from sliding out in a rearward direction.

In order to safeguard against longitudinal displacement of the calk plate 42 in a

forward direction the tapering rear section 37 of the shoe is provided with a recess or cavity 49, designed for engagement by a boss or protuberance 50, which is conveniently struck up from, or formed on, the inner surface of the said calk plate.

The thickness of the wedge or key 45 and the drawing action thereby exerted coöperate in holding the outer jaw 44 of the plate 42 and preventing it from sagging or slipping down. The upper inner corner of the key is also caught within the obtuse angle formed by the inclined outer face or bevel 38 of the dovetailed section 37 of the shoe and the vertical edge 40 of the latter, and thus the key is precluded from creeping up, or working loose.

By preference, the heel calk herein described is drop-forged with the said pair of jaws straight, that is, perpendicular to its upper face, as shown in Fig. 4, so that the several angles and corners of the calk will readily leave the die in which it is made. The jaws 43, 44 are subsequently forced to assume the shape represented in Fig. 3. It will be understood that the narrowest opening only is left between the lips of these jaws to admit of the calk being slipped over the flaring base of the beveled section 37.

30 A square calk 53 has been shown in the drawing herewith, as pertaining to the inner half of the horse shoe and forming an integral part of the same. Obviously, however, it is within the scope of the invention to produce this calk also in accordance with the ideas involved in manufacturing the sharp pointed, separable, outer heel calks herein disclosed.

Figs. 5 and 6 illustrate a slightly modified form of the invention. The outer quarter of the latter-named form of horseshoe (designated by the reference numeral 111 in Fig. 5) has a dovetail end 137, increasing in width downward, similarly to the shoe section 37 before described. That is, it possesses opposed bevels 138, 139 and also a straight vertical edge 140 corresponding to the analogous structural features hereinabove numbered 38, 39 and 40 respectively. 50 In addition, this modified embodiment of the improved horseshoe includes a lateral recess 149 on the inner side of the quarter 111, and the beveled outer face 138 of the latter terminates in a curve vanishing outward, as indicated at 148. The previously described calk plate 142 is employed in connection with the quarter 111, as well as in the other form of shoe, and is applied in substantially the same manner. Thus, referring to Fig. 6, it will be observed that the pair of jaws 143, 144 are arranged to straddle the dovetail section 137. The jaw 143 is received in the recess 149 and firmly held thereby at both ends, from the moment the key 138 is driven in between the opposite jaw 144 of

the plate 142 and the contiguous bevel 140 of the quarter 111. The recess 149 in the present instance is substituted for the fore-mentioned cavity 49 and co-acting protuberance 50, discharging identical functions in a simplified manner. The forward extremity of the key 138 is naturally led outward by the curve 148, in a convenient position to be clenched over the contacting forward edge of the jaw 144.

Having described my invention what I desire to secure by Letters Patent and claim is:—

1. A horseshoe including a heel having a recess formed upon the inner edge thereof, the inner wall of said recess being inclined and the opposite wall of said heel being similarly inclined to form a dovetail, a calk-bearing plate underlying the heel and having oppositely inclined jaws facing the sides of said dovetail, said jaws terminating below the upper face of the heel, and a key insertible between one of said jaws and the outer side of the dovetail opposite the recess to draw the other jaw into the latter.

2. A horseshoe having a heel provided with a recess upon the inner edge thereof, the inner wall of said recess being inclined and the opposite wall of said heel being similarly inclined to form a dovetail, a calk-bearing plate underlying said dovetail and provided with upwardly extending jaws inclined conformably to said walls, one jaw being placed against the inner wall of the recess, while the other jaw is spaced away for its full depth from the opposite wall of the heel, and a wedge-key driven into the space between the last named wall and said other jaw so as to bear directly upon said plate and hold it in position.

3. A horseshoe including a heel having a recess formed upon the inner edge thereof, the inner wall of said recess being inclined and the opposite wall of said heel being similarly inclined to form a dovetail, said opposite wall being provided near its top portion with a straight part forming an obtuse outer angle with the inclined portion thereof, a calk-bearing plate carrying jaws inclined to conform to said dovetail, one jaw entering the recess while the other jaw is spaced away from its corresponding wall of the dovetail, and a key wedged into said space so as to draw said plate against the underside of the heel, the upper edge of said key being prevented by said obtuse angle from creeping up and working loose.

4. A horse shoe including a quarter formed with a cavity in its under face, a calk bearing plate having a protuberance adapted to enter said cavity, jaws on said plate positioned on opposite sides of said quarter, and means causing said jaws with their plate to forcibly grasp the quarter.

5. A horseshoe including a dovetailed

quarter with a recess in the under face thereof and a marginal projection at one side, a calk bearing plate having a protuberance adapted to engage said recess, jaws on said plate inclined conformably to the opposite faces of the dovetail on said quarter, and a key insertible between one of said jaws and one face of the dovetail under said marginal projection, said key operating to draw the other jaw against the other face of the dove-

tail and to press said protuberance into said recess.

Signed at the borough of Manhattan, in the county of New York and State of New York, this 29th day of January, A. D. 1916. 15
